Inventor:
Mervin J. Kelly,
by *Jed C. Palmer* Atty.

UNITED STATES PATENT OFFICE.

MERVIN J. KELLY, OF NEW YORK, N. Y., ASSIGNOR TO WESTERN ELECTRIC COMPANY, INCORPORATED, OF NEW YORK, N. Y., A CORPORATION OF NEW YORK.

ELECTRON-DISCHARGE DEVICE.

Application filed August 31, 1922. Serial No. 585,370.

To all whom it may concern:

Be it known that I, MERVIN J. KELLY, a citizen of the United States, residing at New York, in the county of New York, 5 State of New York, have invented certain new and useful Improvements in Electron-Discharge Devices, of which the following is a full, clear, concise, and exact description.

This invention relates to electron discharge 10 devices and especially to high voltage rectifiers.

In order that a rectifier operate at its maximum efficiency, it is essential that the cathode and anode be closely adjacent to each 15 other. The cathode is usually a highly flexible filament, and under the influence of the alternating field impressed between it and the anode, is subject to considerable vibration. Unless this vibration is prevented, the 20 cathode, due to its closeness to the anode, is apt to contact therewith and short-circuit the device.

An object of this invention is to limit the 25 vibration of the filament under the influence of the electric field.

Referring to the drawing:

Fig. 1 is a side elevation of an electron discharge device embodying the invention;

Fig. 2 is a view of the electrode assembly 30 in transverse section.

The device comprises an enclosing vessel 10 having a reentrant stem 11, upon which is arranged a metallic collar 12 and anode 13 of the flattened cylinder type supported 35 from the collar 12 by means of the supports 14. A block 15 of insulating material, preferably lavite, is supported from the upper end of the anode, and a similar block 16 is supported from the lower end. In the upper 40 block 15 are provided hooks 17, and in the lower block 16 are provided similar hooks 18. A filament 19 is strung back and

forth between these hooks and is arranged in the medial plane of the anode.

Carried by the lower block 16 and extending to approximately the midpoint of the anode, are rods 20 and 21 which are arranged on opposite sides of the filament 19. These rods are formed of resilient material capable of withstanding the high temperature to which it is subjected, without losing its resiliency, such, for example, as molybdenum. Carried by the upper ends of the rods 20 is an insulating member 22, preferably quartz, which extends across one side 55 of the filament; a similar member 23 is carried by the rods 21. These two members clamp between them the strands of the filament 19 and effectively prevent substantial 60 vibration of the strands.

The invention claimed is:

1. In an electron discharge device, an anode, a cathode, a pair of insulating members gripping said cathode intermediate its ends to prevent vibration thereof. 65

2. In an electron discharge device, a cathode, an anode comprising a pair of parallel surfaces, a pair of insulating members supported from one end of said anode, and gripping said cathode intermediate its ends 70 to prevent vibration thereof.

3. In an electron discharge device, an anode having parallel surfaces, a block of insulating material supported by said anode, a cathode interposed between said surfaces, 75 and a pair of insulating members supported from said block and gripping the filament intermediate its ends, to prevent the vibration thereof.

In witness whereof, I hereunto subscribe 80 my name this 25th day of August A. D., 1922.

MERVIN J. KELLY.
